UNITED STATES PATENT OFFICE.

JOHN L. SOMMER, OF NEWARK, NEW JERSEY, ASSIGNOR TO J. L. SOMMER MANUFACTURING CO., A CORPORATION OF NEW JERSEY.

DESIGN FOR A SHOE HORN AND BUTTON HOOK.

47,762.

Specification for Design. Patented Aug. 24, 1915.

Application filed June 25, 1914. Serial No. 847,316. Term of patent 14 years.

To all whom it may concern:

Be it known that I, JOHN L. SOMMER, a citizen of the United States, residing at Newark, in the county of Essex and State of New Jersey, have invented a new, original, and ornamental Design for a Shoe Horn and Button Hook, of which the following is a specification, reference being had to the accompanying drawing, forming part thereof.

Figure 1 is a side view of a shoe horn and button hook of my new design, and Fig. 2 is an edge view of the same.

I claim:

The ornamental design for a shoe horn and button hook, as shown.

JOHN L. SOMMER.

Witnesses:

JOHN T. MORLOCK,
CHARLES MUNTRICK.
